COMBINED FLASHLIGHT AND DETACHABLE
PUMPKIN MASK THEREFOR

Perry Feuer, Roslyn, N.Y., assignor to Creative Creations, Inc., New York, N.Y.

Filed Feb. 25, 1971, Ser. No. 119,075

Term of patent 14 years

Int. Cl. D26—02

U.S. Cl. D48—24 A

FIG. 1 is a perspective view of a combined flashlight and detachable pumpkin mask therefor showing my new design;

FIG. 2 is an exploded perspective view thereof;

FIG. 3 is a front elevational view thereof;

FIG. 4 is a side elevational view thereof, the flashlight being omitted for convenience of illustration.

I claim:

The ornamental design for a combined flashlight and detachable pumpkin mask therefor, as shown and described.
